UNITED STATES PATENT OFFICE.

HARDIN HETH LITTELL, OF LOUISVILLE, KENTUCKY.

RAILROAD-RAIL.

SPECIFICATION forming part of Letters Patent No. 319,278, dated June 2, 1885.

Application filed June 23, 1884. (No model.)

To all whom it may concern:

Be it known that I, HARDIN HETH LITTELL, a citizen of the United States, residing at Louisville, in the county of Jefferson and State of Kentucky, have invented and produced a new and original Design for Sectional Rails for Railroads, of which the following is a specification, reference being had to the accompanying drawings, forming part thereof.

- 10 Figure 1 is a sectional elevation of my newly-designed sectional rail, showing a rounding center-guide bearing. Fig. 2 is a sectional elevation of the same, showing a A-shaped center-guide bearing. Fig. 3 is a sectional 15 elevation of the lower or stationary rail. Fig. 4 is a sectional elevation of the top or movable rail. Fig. 5 is a top plan view of the bottom rail, B, showing the elongated holes D, through which is bolted the top rail, A. 20 These elongated holes D are designed to allow the expansion and contraction of the rails in addition to securing firmly the two rails with the bolts, these five views being deemed necessary to fully illustrate my design. 25 The leading features of my design consist in the raised center guide on lower rail, B, and the recess to correspond on the upper rail, A, together with the bolt-holes C in upper rail and elongated holes D in lower rail, which are 30 for the purpose of fastening the rails together and allowing for expansion and contraction. The rails are thus made in sections, so that the lower rail, B, may be permanently placed in position and the upper rail, A, placed so 35 that the joints will not come in contact with the joints in lower rail—that is, place them with what is known as "broken joints."

When the top rail, A, is worn out it can be taken off and a new rail put in its place without disturbing the lower rail, B, thus making a saving not only of the metal in the lower rail, but in a saving of the time in removing

and replacing the entire rail from the shoes or stringers.

Another valuable feature is the fact that an iron lower rail, B, may be used and a steel top rail, A, thus having all the benefits of a steel rail at a reduced cost.

It is obvious that the elongated holes might be in the lower flange of the upper portion of the rail, or that the elongated holes might be in both the upper flange of the lower portion and the lower flange of the upper portion without departing from the spirit of the invention.

I am aware that a double rail has been made similar to mine, and such double rail is not claimed, broadly. Still I believe myself to be the first to unite the upper and lower sections of such a rail with bolts extending through an elongated hole in the lower flange of the upper rail; and

What I claim is—

In a double rail for car-tracks, the combination of the lower portion, B, constructed with a flattened lower bearing for supporting the rail on the foundation, a thin portion connecting the top with the bottom face of the rail, said top being provided with a flattened broadened surface provided with elongated holes, said surface also provided with a tongue which registers with a corresponding groove in an upper portion, with an upper portion provided with a groove beneath the bearing for the tread of the car-wheels, and also provided with perforations through which pass bolts which unite said upper and lower portions by their flanges, and the bolts C, as set forth.

HARDIN HETH LITTELL.
